UNITED STATES PATENT OFFICE.

BETTIE MITCHUM, OF HAMMONSVILLE, KENTUCKY.

CHURN.

SPECIFICATION forming part of Letters Patent No. 408,126, dated July 30, 1889.

Application filed July 5, 1888. Serial No. 279,140. (No model.)

To all whom it may concern:

Be it known that I, BETTIE MITCHUM, a citizen of the United States, residing at Hammons-ville, in the county of Hart and State of Ken-5 tucky, have invented certain new and useful Improvements in Churns; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

This invention has relation to churns; and 15 it has for its object the construction of a device of that character which will be capable of accomplishing its purpose in the shortest possible space of time and with the least exp- 20 ense of physical force, and also in which the entrance into the churn-body of any insects, dust, or dirt, and of the escape from said churn-body of its contents in churning, will be prevented.

The invention consists in certain novel fea- 25 tures in the construction, arrangement, and combination of parts, substantially as will be hereinafter fully described, and particularly pointed out in the subjoined claims.

In the accompanying drawings, illustrating 30 my invention, and in which the same parts of the several views are designated by the same letters of reference, Figure 1 is a vertical section of my invention, showing the relative position of the parts thereof; and Fig. 2 is a 35 side elevation, and shows the same located in position on the top of the churn-body.

A designates the upper portion of a churn- 40 body, and B the cover for the same, which latter is formed with the usual perforation to permit the dasher-rod C to enter the churn- 45 body. The churn-body, cover, and dasher-rod may each be of the usual and well-known construction, and may be made of any suitable size, form, and material.

Mounted on the top of the churn is a spring F, the uppermost extremity of which is pro- 50 vided with a ring or collar f, of sufficient diameter to receive the dasher-rod C, which latter is formed with a flange or extension f', 55 adapting it to rest upon the spring F and hold- 60 ing it against vertical displacement. The 65 spring F is shown in the drawings as formed

of spirally-coiled wire; but it will be quite ob- 70 vious that, although such is the preferred 75 form, I do not wish to be understood as lim- 80 iting myself to it, but reserve the liberty of 85 making the spring of equal diameter through- 90 out its length without departing from the 95 spirit of the invention. This spring F, by 100 reason of its resiliency, serves to automatically 105 return the dasher-rod, and consequently 110 the dasher, to its uppermost or normal position, and it thus, by obviating the necessity 115 for any upward motion on the part of the operator, lessens the manual labor which would 120 otherwise be required, and also renders said 125 operation much more uniform, thereby in- 130 creasing the supply of butter, and at the same 135 time decreasing the time otherwise required 140 in the production thereof.

Heretofore it was found in the operation 145 of churning that the contents of the churn 150 was liable to splash out of and beyond the 155 churn, and thus result in a loss of that quan- 160 tity of butter. Another disadvantage expe- 165 rienced was in the liability of the entrance 170 into the churn of dust, dirt, insects, &c.

In order to obviate these disadvantages, I 175 inclose the spring F in a sack or cover G, which 180 may be made of leather, water-proof cloth, or 185 paper, or any other suitable material. This 190 sack or cover G is preferably made with a series 195 of folds g, having the angular projections g' be- 200 tween each pair thereof, as shown in the draw- 205 ings. Within these angular projections g' 210 the coils of the spring F are located. The 215 sack or cover G is provided at its upper ex- 220 tremity with a ring or collar H, which has 225 frictional contact with the ring or collar f of 230 the spring F, and serves to secure said sack 235 or cover and the spring together at their up- 240 per extremities. The lower end of this sack 245 or cover is confined between rings or disks D 250 and J. These rings or disks are each formed 255 with holes registering with each other and 260 with the perforation in the churn - cover, 265 through which the dasher-rod passes. They are 270 respectively formed with depending spring- 275 arms E and J', adapted to engage each other 280 and hold the rings or disks in proper position, 285 as clearly shown in the drawings. This means 290 of securing the disks together permits them 295 to be removed and replaced simply by pull- 300 ing the arms J' outwardly and raising or low-

ering, as the case may be, disk J. The ring D is removable from the churn-cover in the same manner.

It will thus be seen that the sack or cover G can be readily and easily removed from and replaced around the spring F. It will further be seen that by reason of the fact that the said sack or cover is connected at its upper end with the top of the spring F said sack and 10 spring will move in unison.

Although I have shown the sack or cover G formed with a series of folds with angular projections between them to receive the coils of the spring, it will be quite obvious that, if 15 desired, it may be made of some soft material loosely encircling said spring and still be capable of extension and depression to permit it to move in unison with the spring.

Having now described my invention, what I 20 believe to be new, and desire to secure by Letters Patent, and what I therefore claim, is—

1. In a churn, the combination, with the top thereof and a dasher-rod having a flange or extension, of a spiral spring mounted on said 25 churn-top and having a ring or collar at its upper extremity serving as a rest for said flange, and a sack or cover having angular projections to receive the coils of the spring and having, also, a ring or collar at its top, 30 for the purpose set forth.

2. In a churn, the combination, with the top thereof and a dasher-rod, of a ring or disk D, having depending spring-arms E, and a ring or disk J, likewise having spring-arms J', all substantially as and for the purposes herein 35 set forth.

3. In a churn, the top thereof, a spiral spring mounted on said churn-top, and a dasher-rod, in combination with rings or disks D and J, having depending spring-arms E and J', re- 40 spectively, and a sack or cover encircling the spiral spring formed to move in unison therewith and having its upper end secured to the dasher-rod and its lower end located between the rings or disks D and J. 45

4. The combination, with a churn-top, of a spring mounted thereon, a dasher-rod having a flange adapting it to rest on said spring, and a sack or cover encircling said spring and having its upper extremity secured to said spring, 50 whereby the latter and said cover will move in unison.

In testimony whereof I affix my signature in presence of two witnesses.

BETTIE MITCHUM.
